UNITED STATES PATENT OFFICE

2,349,634

CONTROL MEANS FOR THE IMPRESSION ROLLERS OF DUPLICATING MACHINES

Morris P. Neal, Quincy, Ill., assignor to Ditto, Incorporated, Chicago, Ill., a corporation of West Virginia

Original application April 7, 1939, Serial No. 266,518. Divided and this application October 25, 1941, Serial No. 416,543

3 Claims. (Cl. 101—132)

My invention relates to duplicating apparatus and particularly to an improved form of black-line duplicating apparatus employing a drum having a master sheet thereon in the form of a thin sheet of aluminum or the like upon which a suitable repellent may be spread for controlling the effective application of ink to the sheet. My present improvements are not, however, to be restricted to use in connection with this type of machine, so far as they are applicable to other types of machines. 5 10

It is the object of this invention to provide an improved form and arrangement of operating and control parts in a machine of this type whereby the operator is enabled easily and quickly to throw the impression roller out of operative pressure relationship with the drum, this result being attained preferably without stopping the rotation of the drum. In my improved arrangement, I have provided a hand lever by a stroke of which the impression roller is moved out of engagement with the drum, the sheet feeding means is silenced, and the roller by which the ink is applied to the master sheet is moved outwardly so as not to engage the master sheet. The arrangement is such that upon a reverse stroke of the hand lever the parts are restored to their operative positions.

For carrying out these objects, the impression roller is supported by a yoke which is pivotally mounted below the drum, means being provided for limiting the upward movement of the impression roller toward the drum, and spring means being provided for applying yielding pressure upwardly on the impression roller for pressing the roller firmly against the portion of the drum which it is designed to engage. Means is provided in connection with the hand lever whereby a downward stroke of the lever causes the yoke to swing downwardly for carrying the impression roller downwardly against the action of said spring means out of position for engagement with the drum.

It is another object of this invention to improve devices of this type in sundry details hereinafter pointed out. The preferred means by which the several objects have been attained are illustrated in the accompanying drawings, in which

Fig. 1 is a vertical sectional view through a duplicating machine embodying my improved construction, with the upper part of the machine broken away and with parts omitted for clearness of illustration:

Fig. 2 is a view similar to Fig. 1 but with some ~~as~~

of the parts in changed position and with additional parts omitted:

Fig. 3 is a top plan view of the impression roller and its supporting and adjusting means, some of the supporting frame parts being shown in section; and

Figs. 4, 5 and 6 are vertical sectional views taken substantially at the line 4—4, the line 5—5, and the line 6—6, respectively, of Fig. 3.

10 This application is being filed as a division of
my earlier application Serial No. 266,518, filed
April 7, 1939, to which reference may be had for
a more complete understanding of the machine
and an appreciation of the relation of the invention
15 covered by this application to the construction
and operation of the machine as a whole.

Referring now to the several figures of the drawings, in which corresponding parts are indicated by the same reference characters, 10 in-

20 dicates the framework of the machine for supporting a drum rotatably in position. In the arrangement shown, the drum comprises two sections 11 and 12, which are rigidly connected together by any suitable means so as to provide 25 openings in the wall of the drum at opposite sides thereof. The drum section 11 is provided with a master sheet 13 wrapped thereabout and secured thereon by any suitable mechanism, not shown. The drum section 12 is provided with an

shown. The drum section 12 is provided with an ink pad 14 wrapped thereabout and secured also by any suitable means. The drum section 11 is of slightly greater diametrical size than that of the section 12. A large gear 15 is connected with the drum at one end portion for driving it in counterclockwise direction in Figs. 1 and 2 from any suitable source of power. Below the drum comprising the sections 11 and 12, I have pro-

vided a platen or impression roller 16 mounted so as to be movable toward and from the drum.

40 In the arrangement illustrated, the impression roller 16 is rotatably mounted upon two arms 17 which in turn are pivotally mounted at 18 so as to be adapted to swing vertically toward and from the drum. At the rear end portions, the arms 17 are connected by a transversely extending cross-bar 19 which is formed integrally with the arms 17 so as to give the structure as a whole the form of a yoke.

45

As is best shown in Fig. 4, the cross-bar 19 of the yoke structure is connected by means of a link 20 with a cross-bar 21 which is secured at its end to suitable portions of the framework 10. The link 20 extends through an opening in the bar 21, with nuts 22 secured by means of screw threads on its lower end below the bar 21 so as

to be adjustable for controlling the height to which the cross-bar 19 is movable. Bars or plungers 23 are also slidably mounted in the cross-bar 21 with nuts 24 adjustably secured on their lower ends for adjusting the vertical position of the plungers with respect to the bar. At their upper ends, the plungers 23 are provided with notched blocks 25 which engage the lower edge of the cross-bar 19 of the yoke, coil springs 26 being mounted upon the plungers for holding them normally in raised position with respect to the bar 21. In the arrangement shown in Fig. 1, the springs 26 press the impression roller 16 firmly against the master sheet 13 carried by the drum section 11.

The means provided for moving the arms 17 and the impression roller 16 downwardly against the action of the springs 26 comprises a long hand lever 27 which is fixedly mounted upon a rock shaft 28 extending across the machine from one side to the other, as is best shown in Fig. 3. At intermediate points therealong, the shaft 28 is provided with pins 29 projecting rearwardly therefrom into position to engage openings in brackets 30 extending downwardly from the cross-bar 19 of the yoke, the arrangement being such that when the lever 27 is moved downwardly from its normal position as shown in Fig. 1 to the changed position as shown in Fig. 2, the pins 29 are moved into changed angular position so as to carry the yoke and the impression roller 16 downwardly against the action of the springs 26 so as to carry the impression roller out of position for engagement with the drum section 11. A long coiled spring 31 connected with the forward end of the lever 27 normally holds the lever in position as shown in Fig. 1.

The nuts 22 are normally adjusted in such position on the link 20 as to permit the impression roller 16 to have a pressure engagement with the drum section 11 but so as to hold the impression roller 16 out of engagement with the ink pad 14 carried by the drum section 12.

Means is provided for holding the lever 27 releasably in its lowered position as shown in Fig. 2. This means comprises a latch device 32 pivotally mounted upon a plate portion 33 of the framework as shown in Figs. 3 and 5, a spring 34 being provided in connection with the latch device for holding it normally swung to the limit of its motion toward the left in Fig. 5. The arrangement is such that when the lever 27 is moved downwardly, the latch device 32 is displaced toward the right so as to assume latching engagement with the lever. A pin 35 slidably mounted in a suitable portion of the framework 10 is adapted by engagement with the latch device 32 to move it toward the right out of engagement with the lever 27 so as to permit the lever 27 to be raised by the spring 31 whenever desired.

In the arrangement as shown in Figs. 1 and 2, a table 36 is provided adapted to hold a pile of copy sheets 37 in position to be fed forwardly by a roller 38 which is mounted in position to engage the top sheet of the pile on the table. A tray 39 is also shown in position in Fig. 1 a

short distance in front of the impression roller 16 for receiving the copy sheets after their passage between the drum section 11 and the impression roller 16. Inasmuch as these parts form in and of themselves no part of the present invention, it is believed to be unnecessary to describe the parts or their operation more completely herein.

While the form and arrangement of parts as shown and described are preferred, the invention is not to be limited to such construction except so far as the claims may be so limited, it being understood that changes might well be made in the construction without departing from the spirit of the invention.

I claim:

1. In a duplicating machine, the combination of a drum rotatably mounted in position, means for mounting a master sheet on the face of the drum, a heavy yoke member having its arms pivotally mounted below said drum, an impression roller journaled between the arms of said yoke in position to engage a master sheet on said drum, vertically positioned bars slidably mounted below said yoke member having notched heads engaging the crossbar portion of the yoke member, springs on said bars normally urging them upwardly for pressing the impression roller against the drum, and nuts adjustably mounted on said bars for limiting the upward movement of said impression roller by said springs.

2. In a duplicating machine; the combination of a drum rotatably mounted in position, means for mounting a master sheet on the face of the drum, a heavy yoke member having its arms pivotally mounted below the drum, an impression roller journaled between the arms of said yoke in position to engage a master sheet on said drum, means comprising springs adapted by engagement with said yoke member normally to hold said impression roller in pressure relationship to said drum, movably mounted pins operatively engaging the crossbar portion of said yoke, and means for moving said pins so as to force said impression roller outwardly away from the drum against the action of said springs.

3. In a duplicating machine, the combination of a drum rotatably mounted in position, means for mounting a master sheet on the face of the drum, a heavy yoke member having its arms pivotally mounted below the drum, an impression roller journaled between the arms of said yoke in position to engage a master sheet on said drum, means comprising springs adapted by engagement with said yoke member normally to hold said impression roller in pressure relationship to said drum, a rock shaft journaled in position adjacent to said impression roller, pins carried by said rock shaft adapted upon a rotary movement of the shaft in one direction to apply pressure on the crossbar portion of said yoke for moving said impression roller out of pressure relationship with the drum, and a lever fixedly mounted on said rock shaft for giving the rock shaft an operative stroke.

MORRIS P. NEAL.
